3 Sheets-Sheet 2

This technical drawing illustrates a mechanical assembly, possibly a cylinder or pump, featuring a central vertical rod (45) with a piston (46) at the bottom. The rod is connected to a lever system (47, 39, 48) which actuates a valve or gate (61, 63, 64) at the bottom right. The assembly is mounted on a base (59) and includes a top cap (28) secured by a locknut (29). A rod (31) extends from the top cap to a lever (34) on the left side. The left side also features a piston rod (35) connected to a piston (33). The right side of the assembly includes a piston rod (56) connected to a piston (53). Various other components are labeled with numbers such as 22, 32, 57, 73, 52, 53, 49, 46, 45, 74, 47, 39, 36, 37, 62, 63, 64, 38, 59, and 61.

MEANS FOR GRIPPING AND LIFTING
STRIP MATERIAL

Jack Breslav, New Haven, Conn.

Application October 18, 1944, Serial No. 559,320

7 Claims. (Cl. 294—81)

1

This invention relates to means for grippingly engaging and lifting relatively thin and long strips of material, such as metal, from supports, such as conveyors, or from piles of such strips of material wherein the strips are resting directly one upon the other. More particularly the features and principles of this invention are adapted for use in combination with annealing or other heat treating furnaces wherefrom or whereto said strips are fed and due to their physical characteristics may be distorted to some extent either lengthwise or crosswise.

With particular reference to metal strips it is well known that due to the effects of the heating thereof in furnaces and also after rolling the same between pressure rollers internal strains are released or set up in the structure of the strips which cause distortion of the same. Such distortions often take the form of irregular waves, which may extend either lengthwise or crosswise of the strips. Being relatively thin such strips are, to some extent, flexible and, unless carefully gripped, will bend if not engaged at properly spaced apart points along their length.

Another object of this invention is to provide new and useful means for gripping and lifting relatively long thin strips of material and particularly strips which have become distorted as above referred to.

Still another object of this invention is to provide a strip engaging and lifting mechanism which is adapted to use in lifting distorted strips relatively short in length and wherein provision is made to adjust the same for strips of different thickness.

A further object of this invention is to provide an improved means for gripping and lifting strips of material which will be relatively simple in construction, inexpensive to manufacture, readily manipulated, compact, and very efficient and durable in use.

With these and other objects in view, which will appear as the description proceeds, there has been illustrated in the accompanying drawings a form in which the features and principles of this invention may be embodied in practice, it being understood that various changes may be made within the scope of what is claimed without departing from the spirit of the invention.

In the drawings:

Figure 1 is a side view of a strip gripping and lifting mechanism wherein the features and principles of this invention are embodied;

Figure 2 is an end view of the mechanism shown in Figure 1;

2

Figure 3 is an enlarged side view of a strip engaging and carrying device embodying certain features of this invention and which is included in the mechanism shown in Figures 1 and 2;

5 Figure 4 is an end view of the device shown in Figure 3;

Figure 5 is a sketch showing the application of the mechanism of this invention to a strip distorted lengthwise;

10 Figure 6 is a sketch showing the application of the mechanism of this invention to a strip distorted crosswise; and

Figure 7 is a sketch showing the use of the device shown in Figures 3 and 4 for gripping and 15 lifting relatively short thin strips.

Referring now to the drawings wherein like reference characters designate like parts throughout the several views, the reference numeral 11, Figures 1 and 2, denotes, in its entire-

20 tirety, a framework for supporting a crane 12 which includes the usual beam, or beams, 13 having supporting wheels 14 adapted to ride on tracks 15 provided at each end of the framework 11, the usual motor 16, cable drum 17, cables 18 and 19, cable blocks 21, and a load carrying hook 22 hung from each block.

One side of the framework 11 is arranged to overhang a conveyor comprising a framework 23 supporting a plurality of rollers 24, which

30 rollers may be driven by a chain (not shown) from a suitable source of power (not shown), but in driving engagement with sprockets 25 secured to the shafts 26 of the rollers 24. The other side of the framework 11 may overhang a plu-

35 rality of piles 27 of strip material piled one strip directly upon the other. The conveyor may be arranged to lead into, or out of, a rolling mill, or a heat treatment apparatus, such as an annealing furnace, whereby the strip gripping and

40 lifting mechanism of this invention may be used either to remove the strips 28, one at a time, from the piles 27 and place them on the conveyor; or to remove the strips from the conveyor and pile them in piles, or upon trucks (not shown).

45 The strips of material 28 may be distorted lengthwise as indicated in Figure 5, the extent of such distortion being exaggerated for the purpose of illustration, or may be distorted crosswise as indicated in Figure 6, also exaggerated. In both instances it is desirable to simultaneously

50 engage and firmly grip the strip at the distorted point as well as at an undistorted point, so that the strip may be lifted uniformly along its entire length.

55 The strip gripping and lifting mechanism illus-

trated in Figures 1 and 2, in association with the framework 11 and the crane mechanism 12, is adapted to engage the thin long strip 28 at a plurality of spaced apart points along its side edges. As the strip 28 is relatively long, in this instance, two gripping devices, such as shown in Figures 3 and 4, are required. These strip gripping devices are securely connected together by welding, or otherwise securing, a load bar 29 to a pair of spaced apart supporting plates 31 of each device. The pairs of plates 31 extend above the bar 29 and have a bolt 32 extending between the plates of each pair. Each of the hooks 22 pass between the plates of each pair and supportingly engage the bolt 32 thereat, whereby the load bar 29 and the pairs of plates 31 are supported by, and may be moved with, the crane 12, being raised and lowered by proper manipulation of the cables 18 and 19 by means of the motor 16 acting on the drum 17.

The pairs of plates 31 also extend below the load bar 29 and the plates of each pair are secured together by a cross-bar 33, preferably welded to each. A balancing bar 34 is disposed between the plates of each pair 31 being pivoted thereto by a bolt, or pin, 35 located intermediate the ends of the bar 34. Referring more particularly to Figures 3 and 4, the strip gripping device further includes a pair of stock engaging grabs. Each grab comprises juxtaposed members 36 and 37, each member having a strip edge engaging jaw 38 extending downwardly from its outer end. The members 36 and 37 are slidably supported in a bracket 39 for horizontal movement, and are adapted to be actuated to move the jaws 38 toward and away from each other to grip and release, respectively, a strip 28 disposed therebetween.

In this instance, the members 36 and 37 are adapted to be actuated to move horizontally the respective jaws thereon by providing ratchet teeth 41 and 42, respectively, upon their upper edges which mesh teeth with gear teeth 43 and 44 respectively, formed on the ends of oppositely directed arms 45 and 46 respectively. The arms 45 and 46 are each pivoted at their toothed ends, to the bracket 39 by pins 47 and 48 respectively, and have their other and outer ends pivoted, by pins 49 and 51 respectively to the outer ends of the arms 52 and 53 respectively. The inner ends of the arms 52 and 53 are pivoted together and to a shackle 54 by a bolt 55. The shackle 54 straddles the ends of the arms 52 and 53 and extends upwardly therefrom in the form of a loop 56 through which a bolt 57 extends which bolt 57 is carried by, and is disposed at, the respective end of the balancing bar 34. The bar 34, in this instance, is formed of two spaced apart strips between which the shackle 54 is disposed to be guided in its vertical movements on the bolt 57 to limit transverse movement of the shackle. The jaws 38 are provided with teeth 58 and, with the teeth 58, extend an equal amount below the bracket 39. The looped portion 56 of the shackle 54, is vertically elongated to allow for vertical lost motion when one grab of a pair (see Figure 5) is required to engage and grip the strip 28 at a level higher than the level to be engaged and gripped by the other grab of this pair.

The jaws 38 of each grab are vertically located, in respect to the edges of the strips 28, by a stop plate 59, which extends along the strip 28, between the jaws 38 and in under and across the bottom of the bracket 39. The stop plate 59 is

suspended from angle bars 61 and 62, secured, as by welding, two on each side of the bracket 39, by threaded studs 63, two studs being secured, as by welding, to the plate 59 at each side of the bracket 39. Adjusting nuts 64, two for each stud and disposed one above and one below the respective angle bar 61, or 62, are provided whereby the plate 59 may be raised, or lowered, to adjust it, and thus vary the amount the jaws 38 engage the edges of the strip 28, and to compensate for different thicknesses of strips. The stop plate 59, when engaging a strip of material which is distorted transversely (see Figure 6), swings the grab to dispose it in position whereby its jaws will properly grip the strip edges.

As indicated in Figure 5, the balancing bar 34 may pivot on the bolt 35, and each of the grabs may pivot on the bolt 57, thus allowing for differences in level between the points, lengthwise on the strip 28, to be engaged by the different grabs carried by the balancing bar 34. As indicated in Figure 6, each grab may pivot on the bolt 55 to tilt out of the vertical and thus operatively engage opposite sides of the strip 28 at different levels, when the strip is distorted cross-wise thereof. In instances where only relatively short strips are to be engaged and the load bar 29 is omitted, the pivot 35 between the balancing bar 34 and the plate 31 may be omitted, whereby the bar 65, see Figure 7, supporting the grabs, will pivot directly on the hook 22.

While the mechanism shown in Figures 1 and 2 is particularly adapted for engaging and lifting a strip 28 which is relatively thin and long, that is, from A to E, it is obviously adaptable for engaging two strips at a time which strips are of a length from A to B and from C to E. It will also be obvious that by connecting the balancing bar 34 of the right hand device to the load bar 29 by a link bolted to each by bolts extending through openings 71 and 72 respectively, a bar of a length from A to D may be efficiently gripped and lifted.

Each grab is provided with a fully automatic jaw release mechanism whereby a strip will be gripped and released automatically without the operator having to touch the strips, or to release the grab jaws. This mechanism includes a hooked rod 73 swingably carried by the arm 52 and a cam mechanism enclosed in a box 74 mounted on the bracket. The construction and operation of the automatic jaw release mechanism used with the mechanism of this invention is fully shown and described in Patent No. 2,337,177, issued December 21, 1943. This release mechanism is so constructed that upon alternate downward movements of the grab, the hooked end of the rod 73, upon entering the box 74, is acted upon by suitable catches and cam surfaces disposed therein to alternately catch the hooked end of the rod 73 to hold the grab jaws open, and to release the hooked end of the rod 73 to permit the grab jaws to close upon the strips. This mechanism therefore constitutes the means to cause alternate gripping and release of the strips of material by the grab jaws 38 at alternate downward movements thereof.

The operation of the above described mechanism is as follows, when it is used to engage and lift a strip of material 28 from a pile 27 and move it to a conveyor, or vice versa, the sheets being piled directly one on top of the other with no spaces therebetween. The crane is moved to dispose the grabs over the strip 28 to be moved. The grabs are then lowered by proper actuation of the motor 16 until all of the stop plates 59 rest upon

the strip 28 at which time the jaws 38 of each grab are spread apart in position to be drawn together to grip the strip 28. The stop plates 59, having been previously adjusted in respect to the bottom edge of the jaws 38 an amount less than the thickness of the strip 28, prevent the jaws 38 from extending below the uppermost strip upon engagement therewith. Assuming that the strip 28 is distorted lengthwise (Figure 5) and crosswise (Figure 6) at various points along its length, the grab, at the highest point in the lengthwise distorted part of the strip, will stop sooner than the grab, at a lower point; the balance bar 34, by pivoting on the bolt 35, permitting the latter grab continuing into engagement with the strip (see Figure 5) at a lower portion thereof.

At portions of the strip 28 distorted cross-wise thereof the grab thereat will transversely swing upon the pivot bolt 55 permitting the jaws 38 to be properly positioned to grip the strip 28 at this point. Upward movement of the load bar 29, and with it the balance bars 34 and the grabs, will cause the jaws 38 to grip the strip 28 and lift it from the pile, or from the conveyor. While raising the strip 28, the grab jaws 38 at the lowermost point thereof will grip the strip first and, after the lost motion between the looped end of the shackle and the bolt has been taken up, the jaws of the other grab will tighten on the highest portion of the strip.

The various pivotal points, and the lost motion arrangement between the shackle and its pivot bolt, together with the adjustable grab stop members included in the mechanism described, provides the means whereby such a mechanism is adapted to efficiently grip and raise thin strip material which is distorted either lengthwise, or crosswise, or both, from, or to, a conveyor onto a pile or from a pile, respectively.

It will be understood that the features and principles of this invention may be embodied in other specific forms without departing from the spirit and essential attributes thereof, and it is therefore desired that the present embodiment be considered in all respects as illustrative, and not restrictive, reference being had to the claims rather than to the foregoing description to indicate the scope of the invention.

Having thus fully described the invention, what is claimed as new and for which it is desired to secure Letters Patent is:

1. In a mechanism for gripping and raising thin strip material, a plurality of grabs spaced apart along the length of said strip, each of said grabs having oppositely horizontally movable strip edge engaging jaws, a load bar, means to raise said load bar, a balance bar for each pair of said grabs and being pivoted at its middle to said load bar, each grab being pivoted to its carrying balance bar and being movable vertically in respect thereto.

2. In a mechanism for gripping and raising strip material a plurality of grabs spaced apart along the length of said strip, a load bar, means to raise said load bar, a balance bar for each pair of said grabs and being pivoted at its middle to said load bar, each grab being pivoted to its carrying balance bar and being movable vertically in respect thereto, each of said grabs having oppositely movable strip edge engaging jaws, stop means to engage the strip to limit the amount said jaws extend over the strip edge, and means to adjust said stop means for different thicknesses of strips.

3. In a mechanism for gripping the edges of

and lifting thin strip material, a bar composed of spaced apart strips, a pair of grabs, each grab including oppositely and horizontally movable jaws adapted to engage opposite edges of the thin strip of material and means to move the jaws toward each other to grip the thin strip at its edges when the grab is raised, a shackle pivotally secured to each grab, each shackle having a vertically elongated loop portion extending upwardly therefrom and extending in between the spaced apart bar strips, means to pivot the loop portion of one shackle to each end of said bar, and means to pivot the bar at its middle to bar lifting means.

15. 4. In mechanism for gripping the edges of and lifting thin strip material, a bar composed of spaced apart strips, a pair of grabs, each grab including oppositely and horizontally movable jaws adapted to engage opposite edges of the thin strip of material, an adjustable stop device disposed between the jaws of the grab and extending across the strip to dispose the jaws in thin strip edge engaging position, and means to move the jaws toward each other to grip the thin strip at its edges when the grab is raised, a shackle pivotally secured to each grab, each shackle having a vertically elongated loop portion extending upwardly therefrom and extending in between the spaced apart bar strips, means to pivot the loop portion of one shackle to each end of said bar, and means to pivot the bar at its middle to bar lifting means.

5. In mechanism for gripping the edges of and lifting thin strip material a bar composed of spaced apart strips, a pair of grabs, each grab including a horizontal bracket, oppositely and horizontally disposed jaw extensions slidably supported by said bracket, a jaw on each extension adapted to engage opposite edges of a thin strip of material, an adjustable stop member extending across in under said bracket and transversely of the strip between the jaws to dispose the jaws in thin strip edge engaging position when said stop engages the upper surface of the strip, and means to move the jaws toward each other to engage and grip the strip at its edges when the grab is lifted, means to connect one grab to each end of said bar, and means to pivotally connect said bar at its middle to a bar lifting means.

6. In mechanism for gripping the edges of and lifting thin strip material a bar composed of spaced apart strips, a pair of grabs, each grab including a horizontal bracket, oppositely and horizontally disposed jaw extensions slidably supported by said bracket, a jaw on each extension adapted to engage opposite edges of a thin strip of material, an adjustable stop member extending across in under said bracket and transversely of the strip between the jaws to dispose the jaws in thin strip edge engaging position when said stop engages the upper surface of the strip, and means to move the jaws toward each other to engage and grip the strip at its edges when the grab is lifted, a shackle having a vertically elongated loop portion extending upwardly therefrom and in between the spaced apart bar strips, means to pivot the loop portion of one shackle to each end of said bar, and means to pivotally connect said bar at its middle portion to a bar lifting means.

7. In mechanism for gripping and raising thin strip material, an elongated bar adapted to extend lengthwise along the strip of material, a plurality of grabs spaced apart along said bar, each of said grabs having oppositely movable

strip-side-edge engaging jaws and being movable only crosswise of the strip, means to pivot said bar at its middle portion to load raising means, each grab being pivoted to said bar and movable vertically in respect thereto, stop means to engage the upper surface of the strip of material at each grab to limit the amount the jaws of the grab extend over the strip side edges, and means to adjust said stop means for different thicknesses of strips.
